UNITED STATES PATENT OFFICE.

RALPH S. JENNINGS, OF BALTIMORE, MARYLAND.

APPARATUS OR MEANS OF DESICCATING TEXTILE OR OTHER FABRICS.

SPECIFICATION forming part of Letters Patent No. 268,495, dated December 5, 1882.

Application filed September 7, 1882. (No model.)

To all whom it may concern:

Be it known that I, RALPH S. JENNINGS, of the city of Baltimore, in the county of Baltimore, of the State of Maryland, have invented 5 a new and useful Improvement in Apparatus or Means of Desiccating Textile or various other Fabrics, and of recovering or utilizing combustible liquids or vapors escaping therefrom; and I do hereby declare the same to be 10 described in the following specification and represented in the accompanying drawings, of which—

Figure 1 is a vertical and transverse section, and Fig. 2 a horizontal section, of apparatus 15 embodying my invention, the nature of which is defined in the claims hereinafter presented. Fig. 3 is a representation of a piece of cloth stretched on a drying-frame, as hereinafter explained.

20 This invention has for its object the expeditious drying of goods or fabrics, particularly such as may have upon them a composition or vehicle containing a volatile oil or liquid—as, for instance, that class of goods known as “gos- 25 samer rubber cloth” or clothing.

Heretofore it has been the practice to dry such goods in the open air, on account of the essential oil or naphtha arising from them in the process of desiccating them, such being injurious to health, and by reason of its inflammable character dangerous to life and property when escaping in a building, and, further, the concentration of the noxious or inflammable vapor in a room with the goods to be dried naturally interferes with the process of drying them. Drying of such goods out-of-doors is generally slow and uncertain, depending much upon the state of the atmosphere, and generally requiring extensive drying-frames and much 35 land therefor.

40 My invention presents a remedy for the difficulties, inconveniences, dangers, and expense resulting from the out-of-doors drying of such articles, and, besides, it affords a means of intercepting and condensing the escaping combustible or noxious vapors, or of utilizing them to advantage. By intercepting and condensing them they can be again used as before; or, instead of thus treating them, they 45 50 may with air be driven into the fire-place of a furnace, and thus be burned to aid in producing heat.

In carrying out my said invention, I make use in a room, R, of suitable racks, stands, or devices for sustaining the cloth or goods to be 55 dried, and properly exposing the surfaces to air driven against them by the rotary fans.

In the drawings, A A represent two stacks of cloth and their supporting-stands B B, having between them one or a series of rotary 60 fans, C, each consisting of a vertical tube, a, supported by a spindle, b, and provided with a series of wings, c, extending from it, (the said tube.) This tube has a series of openings or perforations, d, arranged in it, as shown, between 65 the wings. Into the lower end of each tube a the educt e of an air-blower, D, opens. In each stack the cloths are supposed to be stretched on horizontal frames, and held thereto by tenter-hooks or other suitable means, the 70 several frames being arranged so that the goods or cloths may have spaces between them for the air to pass in contact with their upper and lower surfaces. These pieces of cloth are shown at f and their supporting-frames at g.

75 Between the several rotary fans, or arranged with them, as shown in Fig. 2, are vertical partitions E, whereby the air blown out of each fan will be distributed equally upon the stacks 80 of cloth.

In opposite parts of the room R are vertical tubes F, having perforations h in their sides. These tubes extend from top to bottom of the room, or nearly so, and open at the lower ends into the induction-pipes i of air-blowers G, 85 which, with the blowers D, are arranged in a separate chamber or compartment, S, and discharge by educts k into or through suitable condensers, H, or instead thereof into the ash-pit or fire-place of a furnace. By means of the 90 condensers the gases or vapors in the air driven through said condensers may be reduced so as to be susceptible of being utilized, as herein-before explained.

95 The operation of the apparatus may be thus explained. On the blowers and rotary fan or fans being put in action, air will be driven into and out of the hollow tubes of each of such fans, and by its wings will be disseminated through the spaces between the cloths or articles to be dried, and will rapidly evaporate the naphtha or essential oil of the composition of such goods. The air charged with the vapor will, by the blowers G, be drawn into the tubes 100

F and such blowers, and will be discharged therefrom through the educts k. Were it not for the exhausting-blowers G and the perforated pipes F, the naphtha would collect or 5 be liable to collect in the upper part of the room, to the detriment of the goods, and the air would not be equally disseminated between the cloths or goods.

From the above it will be seen that the 10 whole process of drying the goods and saving the vapors of the essential oil or vehicle used in the composition upon them is conducted in a closed room or rooms without the necessity of persons being therein or exposed to the vapors while the process is being carried on. The 15 goods are very expeditiously desiccated, no matter what may be the state of the outside atmosphere, or the weather be stormy or fair.

What I claim as my invention is as follows:
20 1. The combination of one or more rotary fans, C, and stationary perforated pipes F, arranged, essentially as described, in a room, R, with one or more induction air-blowers, D, and one or more eduction air-blowers, G, provided

with conduits leading from them to the pipe 25 or pipes and fan or fans, all being for use with frames, racks, or suitable appliances arranged in such room, and for supporting goods to be dried, substantially as set forth.

2. The combination of one or more rotary 30 fans, C, and stationary perforated pipes F, arranged, essentially as described, in a room, R, with one or more induction air-blowers, D, one or more eduction air-blowers, G, and one or more condensers, H, all being substantially 35 and arranged and adapted as and for use as set forth.

3. The combination of partitions E, arranged substantially as described, with one or more rotary fans, C, in a room, R, with such fans, 40 and with the perforated pipes F and air induction and eduction blowers D G, all being adapted and to operate essentially as and for the purpose set forth.

RALPH S. JENNINGS.
